UNITED STATES PATENT OFFICE.

ERNEST C. BLAICHER, OF BELMAR, NEW JERSEY, ASSIGNOR TO INTERSTATE SMELTING AND REFINING CO., INC., OF NEWARK, NEW JERSEY.

METHOD OF MAKING FINGER RINGS.

Application filed May 9, 1923. Serial No. 637,778.

To all whom it may concern:

Be it known that I, ERNEST C. BLAICHER, a citizen of the United States, and a resident of Belmar, county of Monmouth, and State of New Jersey, have invented certain new and useful Improvements in Methods of Making Finger Rings, of which the following is a specification.

This invention relates to an improved method of making finger rings, particularly finger rings that are set with stones and which have recesses on the inner faces so that the stones show up to better advantage because the bottoms of the stones are not closely grasped by the ring. The refraction possible in such recessed rings adds much to its appearance and therefore much to its value. Heretofore this kind of ring has been made either by cutting recesses in the ring, which is expensive and unsatisfactory in appearance, or making the ring of two perforated members, one fitting within the other, as in my United States Patent No. 1,492,819, issued July 18, 1922.

In this present invention I make a one-piece ring which has the stamped recesses on its face, and these recesses are inexpensively produced and the whole ring, in fact, is quickly and economically manufactured and also has a finished appearance.

In my method I provide a washer-like ring substantially flat and with recesses on one face, and I then upset this washer to form a cylindrical band, the upsetting being arranged so that the recessed face of the washer becomes the inner face of the band, and then these recessed parts can be pierced to form settings for the stones.

The invention is illustrated in the accompanying drawing, in which Figure 1 is a face view of a washer-shaped ring adapted for use in my method, and Figure 2 is an edge view thereof. Figures 3 and 4 are sections showing the ring in steps of upsetting the washer-shaped ring to form the cylindrical band. Figure 5 is a section similar to Figure 4 with the recessed parts pierced. Figure 6 is an enlarged section on line 6--6 in Figure 1, and Figure 7 is an enlarged section on line 7--7 in Figure 5. Figures 8 and 9 are views similar to Figure 1, but showing modifications of the recessed parts of the washer-shaped ring.

In carrying out my method I provide, by stamping or otherwise, a washer-shaped

ring 10 which I provide with recesses 11. For the purpose of this invention only one face need be recessed, and I illustrate only one face so recessed, but the other face can be left plain or suitably ornamented. The washer-shaped ring is then subjected to pressure, usually by means of dies, to upset the ring to form it into a cylindrical band.

A particular means for carrying out this upsetting process is not shown, since such mechanism is well known to those engaged in handling metals, particularly ductile metals such as are used in finger rings. The upsetting can be done in one operation, but it is preferred, in the case of thin stock, to first put the washer through a step to partly upset it, say to the extent shown in Figure 3, and then through a second step to complete the upsetting, as in Figure 4.

After the ring has been formed into the cylindrical band from the washer-shaped ring, the recesses are symmetrically arranged on the inner side or face of the band and provide the necessary opening for the proper refraction of light by jewels or stones set in the ring, which are set preferably in the center of these recessed parts, and for this purpose the setting is provided by piercing the ring at the desired points, either by drilling or punching or similar means, as shown at 12, and these holes 12 are used by the stone setter for placing the stone, such as a diamond, in the ring, and the stone is thus set in the usual way, this being familiar to stone setters, and the stone and the prongs for holding it are not shown in the drawing, but simply the ring before the stones are set.

These rings are particularly adapted for wedding rings and the like, in some cases the recesses being arranged all around the ring and stones being set all around the ring, but other styles employ only enough stones to cover a part of the circumference, say one-half or one-third thereof, leaving the part of the ring on the inner side of the finger without stones, and when this form of ring is desired the washer can be indented only part way around on one face, as shown in Figure 8, leaving the smooth part 13 which, when forming the inner face of the cylindrical band, provides a space for engraving.

Different forms of recesses can be made in the ring, making it possible to supply

many different designs, only one, however, being shown in the drawing in Figure 9, in which I show the triangular recesses 14.

When recesses are punched in the washer 5 I find that I get the best effect as to the appearance of the stone after it is set, and also provide an easy setting of the stone, by making the recesses 11 inclined toward the center so that the ring is thinnest where 10 the setting 12 comes, since the inner walls of the recesses 11 are inclined toward the center, as shown at 15.

I claim:

1. The method of making finger rings 15 which consists in providing a washer-shaped ring with a recess in one face, and upsetting said ring to form a cylindrical band with the recess on the inner face, whereby the band can be pierced at the 20 recessed part to form a setting.

2. The method of making finger rings which consists in providing a washer-shaped ring, indenting one face thereof to form separated recesses, then upsetting the ring to form a cylindrical band with the recesses on the inner face, and then piercing the band at the recesses to form settings. 25

3. The method of making finger rings which consists in providing a washer-shaped ring, indenting one face thereof to form separated recesses, which recesses terminate short of the inner and outer edges of the ring, then upsetting the ring to form a cylindrical band with the recesses on the inner face, and then piercing the band at the recesses to form settings. 30

In testimony that I claim the foregoing, I have hereto set my hand, this 3rd day of May, 1923.

ERNEST C. BLAICHER.
